U.S. Appl. No. 29/459,212, filed Jun. 27, 2013, Park et al.

Primary Examiner — Mitchell Siegel(74) *Attorney, Agent, or Firm* — Cantor Colburn LLP(57) **CLAIM**

The ornamental design for a shelf for refrigerator, as shown and described.

DESCRIPTION

FIG. 1 is a perspective view of a shelf for refrigerator showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof when in use.

The broken lines are for showing an environmental structure, and form no part of the claimed design.

1 Claim, 6 Drawing Sheets(56)
